UNITED STATES PATENT OFFICE.

GIUSEPPE CASCIOTTA, OF NEW YORK, N. Y.

PLECTRUM PIANO ACTION.

Application filed May 11, 1921. Serial No. 468,560.

To all whom it may concern:

Be it known that I, GIUSEPPE CASCIOTTA, a subject of the King of Italy, and resident of the city of New York, borough of Manhattan, county of New York, and State of New York, have invented a new and Improved Plectrum Piano Action, of which the following is a full, clear, and exact description.

10 My invention relates to a piano action and aims to provide certain new and useful improvements in connection with a device of this character..

It is well understood in certain respects, 15 that the tonal qualities and effects produced by a harp are incapable of being produced in a piano when the strings thereof are subjected to the ordinary percussion action; it being well known that the strings of a harp

20 must be picked.

On the other hand, however, a performer may produce runs and brilliant tones upon a piano in view of the key-board forming a part of this instrument, which permits of 25 these results being accomplished without the expenditure of that amount of energy which would be necessary to produce the same result upon a harp.

It is an object of my invention to provide 30 a novel piano action capable of being substituted for a conventional piano action constructed in a new piano and by means of which the same tonal qualities will be capable of being duplicated by means of a piano as are now capable of being rendered 35 only by a performer upon a harp.

A further object of my invention is the construction of a device of the character stated which shall be extremely simple and 40 by means of which the effects brought out in the preceding paragraph may be accomplished, in addition to the brilliant tones, etc., which were heretofore capable of accomplishment only upon a piano.

45 Further objects of my invention will appear in the annexed specification taken in connection with the drawings, of which latter present practical embodiments of the same, and in which;

50 Figure 1 is a transverse sectional view of an upright piano having my improved type of action mounted therein.

Figure 2 is a fragmentary face view of a section of said action.

Figure 3 is a sectional side view taken 55 along the line 3—3 and in the direction of the arrows indicated in Figure 2.

Figure 4 is a sectional plan view taken along the line 4—4 and in the direction of the arrows indicated in Figure 3. 60

Figure 5 is a sectional plan view of my device as applied to a grand piano.

Figure 6 is a sectional side view thereof taken along the line 6—6 of Figure 5.

Figures 7 to 10 illustrate the successive 65 positions of the essential parts of the action.

Figure 11 is a perspective view of the string contact element.

Figure 12 is an enlarged sectional side view taken along the line 12—12 of Figure 70 6, and

Figure 13 is a plan view of a slightly 75 different form of operating arm which may be utilized to advantage in certain adaptations.

Referring now more particularly to Figure 1 it will be seen that the reference numeral 15 indicates the cabinet of an ordinary upright piano of any design, which in the usual manner is provided with a plurality of keys 16 arranged adjacent each other and constituting in aggregate the key-board, and serving, when operated, to effect a vibration of one of the strings 17, of the harp mounted within the piano. 80

Contrary to the conventional construction a pivot block 18 is arranged within the cabinet 15, and preferably extends through the entire length thereof. 85

Rockingly mounted upon this pivot block 90 are arcuate transmission members 19, which correspond in number to the number of keys 16 provided. In the usual manner the shank 20 of the key is pivotally supported and the contacting surfaces of this 95 shank and the member 19 are preferably covered with felt 21.

A supporting back 22 is rigidly secured to the cabinet 15 and serves to pivotally support a number of actuating levers or 100 arms 23, as has been indicated by the reference numeral 24, it being noted in this connection that the actuating levers or arms 23 also correspond in number to the number

of keys 16 which of course correspond to the number of members 19 utilized, and that each of the latter members has its upper face also covered with felt to contact 5 with a similar face forming part of the actuating levers or arm 23.

Thus a movement of the key 16 downward will result in a rocking of the member 19, and this in turn will serve to depress the lower end of the actuating arm 23, thus swinging the outer end thereof away from the harp 17, all of these directions of movement being indicated by arrows in Figure 1.

15 A release of the key 16 immediately results in the same being returned to its normal position. This is due to the fact that a spring 25 which is interposed between the lower or inner end of each actuating arm 23 and the face of the supporting back 22. It is also to be noted in this connection that an extreme outward swinging on the part of any actuating arm 23 is prevented, preferably by means of a confining member 26 spaced from and extending along the outer faces of the actuating arms, and this confining member is preferably provided with an actuating strip 27 which will preclude any undue noise resulting incident to contact between any actuating arm and the said confining member.

Attention is now invited to Figures 2, 3 and 4. In these views it will be seen that each of the actuating arms 23 is preferably provided with an opening cooperating with a guiding element 28 secured to the supporting back 22. This will obviously prevent any sidewise distortion of the actuating arms at their point of pivotal connection. 40 incident to sidewise strains upon the outer ends of these arms. Further, secured adjacent the outer ends of each of the arms is an operating head 29 connected to the arm 23 in the adaptation illustrated in the figures referred to by means of a flexible strip 30. Thus the head 29 may be swung to either side of a straight line within certain limits for a purpose hereinafter more fully specified.

50 Referring now more particularly to the specific construction of the head it will be noted, reference being had to Figure 12 that the same includes a body portion 31 to which a spring pressed retaining member 32 is pivotally secured, as at 33, adjacent gripping portions of both of these members preferably being covered with felt or a similar substance 34.

60 A pick 35 shown in Figure 11 may thus be firmly and detachably held by the head 29 and the contact portion 36 thereof, which preferably embodies limited flexible qualities extends beyond the outer face of the head. Referring again to Figures 2 to 4 it will also be seen that with a view of provid-

ing a guide for each of the actuating arms for a purpose hereinafter brought out, members 37 are fixedly secured, preferably to the body of the harp, and these members rigidly support guiding elements or fingers, each providing in cross section an oblong curved body portion 38 having its body arranged at an angle to the path of travel of the operating head 29. A similar guiding element 39 is rigidly carried by each of the operating heads 29, and this guiding element has its outer end extending to a point beyond the inner end of the guiding element 38, it being noted in this connection that the body of the guiding element 39 is disposed in a plane substantially parallel to the angle in which the guiding element 38 is disposed.

70 With a view of illustrating the operation accomplished by virtue of the construction aforescribed, attention is invited to the series of Figures 7 to 10 inclusive. It will be seen reference being had to Figure 7 that the operating head 29 lies in a position in which the parts are shown as arranged in Figure 1. By virtue of the fact that the guiding elements or fingers 38 and 39 are also arranged substantially in line with each other, it will be seen in Figure 8 that a depression of one of the keys 16 will result in one of the operating heads 29 moving inwardly, and due to the flexible strip 30 this movement will be continued towards the strings 17. This movement will be continued until the contact portion 36 of the pick bears in intimate contact with the strings 17, and a further movement on the part of the operating head, as has been indicated in arrows will result in the string 17 being picked in a manner similar to the results achieved by means of the fingers of a performer upon a harp.

75 The tendency of the actuating head due to the resilient qualities of the flexible strip 30 will be that of realigning the guiding elements 38 and 39. Thus upon the actuating head being moved to a position slightly beyond that illustrated in Figure 9, i. e., to a point where the guiding elements 38-39 clear each other, the said head will immediately snap back to a point at which the guiding element 39 will lie above and to the left of the guiding element 38. This is to be attributed to the resilient feature forming a part of the actuating arm or lever, and it will be obvious that by this construction an operator may 80 permit the key to return to its natural position without any fear being felt of the pick 36 contacting with the string 17 upon its return stroke, it being further noted that the 85 flexibility of the actuating arm will allow of this displacement of the actuating head in an opposite direction to effect its return to normal position. Thus the string 17 will be cleared by the contact portion of the pick 90 and no tone will result upon the return

95 100 105 110 115 120 125 130

stroke of the operating head to its normal position.

From the foregoing it will be appreciated that I have provided what might preferably be termed a plectrum piano action and by means of which a duplication of the results achieved by a harp may be accomplished. Furthermore it will be seen that this action is extremely simple and efficient, and thus any objection on this point is avoided.

It will be seen that my invention is quickly adaptable to a grand piano and in this connection attention is invited to Figures 5 and 6. The construction illustrated in these figures is entirely similar as far as the actuating heads 29, picks, guiding elements, etc. are concerned, the only difference being that this construction is of even a more simple nature than the construction illustrated in the figures previously referred to.

Thus it will be seen in Figures 5 and 6 that the keys 40 are pivotally secured as at 41 to a supporting back 42, directly overlying the portion of the harp 43. Springs 44 serve to normally depress the outer ends of the arms 45 forming a continuation of the keys 40, downwardly, and suitable guiding elements 46 also co-operating with the keys, it being further noted that co-ordinating elements 47 are preferably provided, which limit a movement of the keys or arms forming a continuation thereof. These arms support flexible strips corresponding to the strips 30 and an actuating head 29 is secured to the outer ends of each of these strips as in the aforescribed construction, the co-operation of the pick secured to each of the operating heads with a string of the harp being in all respects similar to the operation aforescribed in connection with an upright piano.

It will be noted, reference being had to Figure 13 that the strip 30 may be entirely dispensed with if this is desired by forming the actuating arm 45 or 23 of a good quality of wood, and in providing the same with a reduced portion 48, which will thus incorporate flexible qualities to the arm itself, so as to produce the result desired. Furthermore it will be seen that although a number of different shapes of guiding elements might be utilized, that the shape shown is preferably employed by virtue of the fact that the curved surfaces of the same will present smooth guiding faces permitting of a great freedom of movement of the arm, and towards the insuring of a positive guiding action.

Thus it will be seen that my invention is adaptable to any type of instrument, and that no necessity exists of any of the parts being removed in a conventional instrument other than the action, if the results achieved by means of my invention are desired.

Furthermore it will be appreciated that

numerous modifications of structure might readily be resorted to without in the least departing from the spirit of my invention, which I claim as;

1. A piano action including a plurality of pivotally mounted actuating arms, an operating head secured to the outer end of each of said arms, and a resilient portion interposed between and connected to the body of each of said arms and its operating head, said operating head including a body portion, a spring pressed retaining member rockingly secured to said body and a pick interposed between said body and member. 75

2. A piano action including a plurality of rockingly mounted arms, a resilient portion forming a part of each of said arms, an operating head secured adjacent the outer end of each of said resilient portions, and a pick carried by each operating head, each arm having associated therewith guiding means adapted to flex the resilient portion of said arm to one side of a given point upon said arm being swung outwardly, and to the opposite side of said given point upon said arm returning to its normal position. 80

3. A piano action including a movable arm, a string to be picked, a pick carried at the end of said arm adjacent to its string, and means for moving and guiding said arm to cause the pick, in the operation of sounding a note, to describe a closed figure lying in a plane at an angle to the line of extension of the string, said means including a pair of oppositely directed fingers one fixed 95 relative to the arm and one carried by the arm, the latter finger being resiliently mounted on the arm and both fingers being so shaped and arranged that one travels completely around the other during a picking and return movement of the arm, to this end the fingers extending in opposite directions and substantially parallel with portions overlapping transversely of the lines of extension of the fingers and said fingers being connected to their mounting parts beyond such overlap. 100

4. A piano action including a movable arm, a string to be picked, a pick carried at the end of said arm adjacent to its string, and means for moving and guiding said arm to cause the pick, in the operation of sounding a note, to describe a substantially elliptical figure, said means including solely a resilient mounting for the pick and a pair of co-operant fingers one on the mounting last mentioned and the other fixed relative to the first-mentioned finger, one of said fingers being substantially elliptical in cross-section. 115

5. A piano action including a movable arm, a string to be picked, a pick carried at the end of said arm adjacent to its string, and means for moving and guiding said arm to cause the pick, in the operation of 120

sounding a note, to describe a figure substantially elliptical in form and the major axis of which is to one side of the string and in a plane substantially perpendicular to the line of extension of the string, said means including solely a pair of cooperant fingers one carried by the arm and the other fixed relative to the first-mentioned finger, said fingers having their free ends oppositely directed, and the part of the arm carrying one of the fingers being resiliently movable transverse to the plane of movement of the arm in advancing toward the string during the operation of sounding a note, one of said fingers being substantially elliptical in cross-section.

6. A piano action including a movable arm, a string to be picked, a pick resiliently carried at the end of said arm adjacent to its string, and means for moving and guiding said arm to cause the pick, in the operation of sounding a note, to describe a closed figure, said means including solely two cooperant fingers one carried by the arm and fixed relative to the pick and the other finger fixed relative to the first-mentioned finger, one of said fingers being substantially elliptical in cross-section.

7. A piano action including a movable arm, a string to be picked, a pick carried at the end of said arm adjacent to its string, and means for moving said arm to cause the pick, in the operation of sounding a note, to describe a figure substantially elliptical in form and the major axis of which is to one side of the string and in a plane substan-

tially perpendicular to the line of extension of the string, such means including a projection on the pick and a fixed member adjacent to the string for coacting with said projection, said fixed member having a periphery shaped substantially like an ellipse where said member coacts with said projection, the part of said fixed member having such periphery being located wholly to one side of said string.

8. A piano action including a movable arm, a string to be picked, a pick carried at the end of said arm adjacent to its string, and means for moving said arm to cause the pick to pluck said string, such means including a single fixed guiding member on one side of the string having a cross-section elongated more in one direction than in the direction perpendicular to the first-mentioned direction, and a single guided member carried by the pick-carrying end of said arm.

9. A piano action including a movable arm, a string to be picked, a pick carried at the end of said arm adjacent to its string, and means for moving said arm to cause the pick to pluck the string, such means including a projection on the pick and a fixed member adjacent to the string for coacting with said projection, said fixed member having a periphery shaped substantially like an ellipse where said member coacts with said projection, and such projection where it coacts with said fixed member having a periphery shaped substantially like an ellipse.

GIUSEPPE CASCOTTA.
